UNITED STATES PATENT OFFICE

2,156,712

LAUNDERING APPARATUS

Claude J. West, Philadelphia, Pa., assignor, by
mesne assignments, to Theodore Halkias, Phil-
adelphia, Pa.

Application July 26, 1935, Serial No. 33,267

3 Claims.

(Cl. 38—4)

The present invention relates to a certain new and useful laundry ironer and certain new and useful improvements in laundry ironers, and it relates more particularly to continuously operable rotary type laundry ironers.

An object of the present invention is to provide a laundry ironer of high capacity and occupying relatively little floor space (as compared with the present conventional types of laundry ironers) and which will afford the work passing through the machine relatively great traverse with a relatively small transverse dimension machine, so that a more compact and smaller machine may be made to produce the same amount of work as a larger machine now produces.

A further object of the present invention is to facilitate the elimination of moisture from the laundry as it passes through the machine so as to generally increase the speed of the laundering operation.

A further object of the present invention is to provide a machine of simplified construction which will be less expensive to produce, will be more durable and serviceable, and one which may be more efficient in operation and maintenance.

With the above and other objects in view which will appear more fully from the following detailed description and the accompanying drawings, the present invention includes a certain novel arrangement of movable and stationary ironing members and means for coordinating the same.

The present invention further consists of certain novel features as well as details of construction, all of which will appear more fully from the following description and the accompanying drawings.

In the accompanying drawings in which like reference characters indicate like parts:

Figure 1 represents a vertical transverse cross-sectional view of the machine embodying the present invention showing the principal stationary and movable ironing members and their relationship to each other.

Figure 2 represents an end elevational view of a laundry ironer embodying the present invention, viewed in the same direction as the direction in which the view in Figure 1 is taken, but showing the exterior of the machine at that end or side of the machine, to wit, the left end or side of the machine as one faces the front or in-take end of the machine, with some details shown in section.

Figure 3 represents a front elevational view of

the machine partly broken away on the left side.

Figure 4 represents a side elevational view of the machine showing the right side or end of the machine.

Figure 5 represents a rear elevational view of the machine, that is, where the ironed work is discharged.

Figure 6 represents a longitudinal vertical section of the machine taken generally on line 6—6 of Figure 1.

Figure 7 represents a generally vertical longitudinal section on line 7—7 of Figure 1.

Figure 8 represents a perspective view of an upper and lower section of the main steam chests or ironing buck.

Figure 9 represents a perspective view of one section of the auxiliary feed in steam chest or ironing buck and the associated manifold, and the idler feed belt roller associated therewith.

Figure 10 represents a perspective view of a stripper finger.

The machine includes a main roll 11, generally hollow for the reception of steam or other heating medium, if desired, and carried upon the main shaft or pivot 12, although the application of heating medium into the interior of the main roll may be omitted.

The main roll 11 carried upon the pivots or trunnions 12 is supported, along with the other ironing members, between a pair of more or less similar and juxtaposed side frame members 13, 13a and 14, 14a respectively, which carry the bearings for the various shafts and pivots and other supporting structure, and which in turn, are carried upon any suitable base 15.

Below the main roll 11, a generally stationary steam chest 16 is provided, while above the main roll 11, a more or less similar steam chest 17 is provided. The steam chests 16 and 17 are formed of similar adjacent and contiguous sections 18 and 19 respectively, shown particularly in Figure 8, and are here shown of the same form and construction as the sectional steam chests particularly disclosed in my copending application Serial No. 756,517 filed December 7, 1934, now matured into Patent No. 2,057,988.

The steam chests have inner cylindrical surfaces of a radius corresponding to the outer radius of the main roll 11, that is, including not only the body of the main roll but also including the outer padding material 20 of fabric or other padding material which is customarily applied to the roll. The lower steam chest 16 is preferably mounted stationarily both front and back, and in the modification of the present in-

vention shown in the drawings of this application, the bottom steam chest 16 is so mounted, although I may mount the lower steam chest for vertical adjustment about the pivot 21. The 5 upper steam chest 17 is pivotally mounted in relation to the pivot 21 and is arranged for vertical adjustment about said pivot, to gain access to the roll 11.

In the particular modification or embodiment 10 of the invention shown in the drawings herein, the adjustment between the central roll 11 and the corresponding upper and lower steam chest is obtained by the vertical adjustment of the main roll 11 in relation to the lower and generally 15 stationary steam chest 16 and the vertical adjustment of the upper steam chest 17 in relation to the center roll 11. This is accomplished by journalling the main pivots or trunnions 12 in vertically movable bearings or journals 22 and 20 23 carried upon the slides or vertically slidable guides 24 and 25 on the left side of the machine, and 26 and 27 on the right side of the machine, guided in suitable slide bearings or vertical guiding bearings 28 and 29 on the left side of the 25 machine, and 30 and 31 on the right side of the machine, and 30 and 31 on the right side of the machine. The lower bearing supporting slides or guides 25 and 27 extend downwardly into corresponding spring housings 32 and 33, and carry terminal spring anchorages 34 at their lower 30 ends. Similar springs 35 confined between said lower spring anchorages and the upper closures 36 of said spring housings, serve to urge the guides downwardly with yieldable force; the force being dependent upon the springs 35. The 35 spring housings 32 and 33 are pivotally linked or connected to similar eccentric straps 37 and 38 on each side of the machine, which in turn surround similar eccentrics 39 and 40 carried on corresponding pivots 41 and 42, and affixed to corresponding gears or pinions 43 and 44. By 40 turning the latter pinions in unison, the compression of the springs 35 may be increased or decreased equally on the two sides of the machine, thereby uniformly to increase or decrease 45 the pressure between the main roll and the lower steam chest at the will of the operator. By suitable proportioning, the adjustment can be so arranged that by raising the eccentrics completely into their uppermost position, the lower 50 spring abutments 34 will contact the bottoms of the spring chambers or spring housings so as also to raise the journal guides 25 upwardly sufficiently to break the contact between the center roll and the lower steam chest. The upper steam chest 17 pivoted at 21, is similarly controlled by a pair of opposite and similar pressure devices indicated particularly in Figures 2 and 4, including the spring actuated or otherwise suitably actuated plungers 45 and 46, which are 55 provided with similar terminal spring anchorages 47 within similar spring housings 48 and 49 which are urged downwardly by similar springs 50 within said housing and which are connected with the opposite ends of the upper steam chest 60 17 through the connecting rods 51 and 52 adjustably secured to the plungers 45 and 46 and pivotally connected to the steam chest through the pivots 53 and 54, and the bearing caps 55 and 56. The spring housings 48 and 49 are provided at 65 their lower ends with the eccentric straps 57 and 58 respectively, which may be formed integrally with the spring housings and which surround similar eccentrics 59 and 60 carried upon the shaft 61 which extends beneath the machine 70 75 from one side to the other and thus synchronizes

the adjustment on the two sides of the machine. The shaft 61 also carries gears or pinions 62 and 63 which mesh with the gears 43 and 44 respectively, and also mesh with similar gears for the third pressure adjustment of the machine so that all pressure adjustments are synchronized or correlated. The shaft 61 also carries a worm gear 64 which is in mesh with a worm 65 upon the control shaft 66, the front end of which carries an adjustment handle or wheel 67 through which the pressures are thus simultaneously adjustable.

The auxiliary feed-in roll 68 is also preferably mounted for vertical adjustment in relation to the auxiliary feed-in steam chest 69 which is 15 stationarily mounted between the intermediate side frames 13a and 14a of the machine and which is formed of sections in a manner similar to the lower and upper main steam chests 16 and 17. Thus, the pivots or trunnions 70 of the 20 auxiliary roll 68 are journalled in suitable journals 71 and 72, which may be of the bushing type or the anti-friction or roller type as indicated, and which in turn, are carried by the vertical slides 72a and 73 on the left hand side, 25 and 74 and 75 on the right hand side, which are suitably guided in the stationary guides 76, 77, 78 and 79. The lower guides 73 and 75 are adjustably connected to similar spring plungers or other suitably actuated plungers 80 and 81 which 30 enter the similar spring housings 82 and 83 which are arranged in a manner similar to the spring housings 32 and 33 although proportioned to suit the pressures required between the auxiliary roll and its steam chest. The spring housings 82 and 35 83 are similarly connected to similar eccentric straps 84 and 85 carried upon eccentrics 84a and 85a on the pivots 86 and 87, and which pivots are geared to the control gears through the pinions 88 and 89, respectively. Thus, the pressure 40 can be increased or decreased simultaneously by the single manual control 67 between each of the rolls and their respective steam chests, and the contact may be broken by elevating the eccentrics until the bottom spring anchorages of 45 the spring plungers abut the bottoms of the spring chambers, and then raising the eccentrics suitably beyond that point.

The auxiliary roll 68 is preferably also provided with similar padding 90 about its outer 50 circumference. In advance of the feed-in roll 68, an endless feed-in apron 91 is provided, formed sectionally as indicated in Figure 3, each of a small part of the total width of the machine, and the sections lying closely adjacent to 55 each other as indicated, so as to constitute a more or less continuous apron across the full width of the machine; said apron extending around a driving roll 92, an idler roll 93, having a fixed pivotal axis, and the idler roll 94 immediately adjacent the feed-in roll 68 which is supported by the notched ears 94a integral with the upper forward portion of the vacuum and steam chest 69, and the idler roll 95 having its axis shiftable so as to vary the tension in the 60 apron or so as to vary the amount of slack or absence of slack in the apron. The ears 94a also effect spacing and guiding means for the belts 91. The adjustment of the roll 95 may be effected by any suitable adjustment means, such as 65 supporting the journal blocks upon adjustment screws 96, and providing the same also with the adjustment screws 97 whereby the setting may be fixed or blocked against the tension of the belt.

The belt is arranged to travel generally in the direction of the arrow 98 while the feed-in roll 68 is arranged to travel generally in the direction of the arrow 99, while the main roll is arranged to travel generally in the direction of the arrow 100.

The bottom steam chest 66 is provided with a lower and outer ironing surface 101 which may be formed of sheet metal bent around the lower steam chest and supported upon the spacer webs 102, 103, 104, 105 and the steam manifold 106 in the manner indicated particularly in Figure 1. An auxiliary ironing apron 107 is provided beneath the plate 101 and in contact with the outer convex surface thereof, as indicated particularly in Figure 1, being carried by the driving roll 108 and the idler roll 109 upon a fixed axis and the idler roll 110 adjustably carried upon the bearing brackets 111 and adjustably by means of the adjustment screws 112, and further secured by the set screws or bolts 113 and 114 by which the adjustment can be fixed and locked. The belt is adapted to travel in the direction indicated by the arrows 115, thereby discharging the work generally in the direction of the arrow 116 onto any suitable table 117 indicated in a fragmentary way in dotted lines in Figure 1. The belts 107 at the forward portion of the machine are spaced from each other and guided by the pins 107a secured to the rod or bar 107b supported by the intermediate frames 13a and 14a.

The machine is driven from any suitable source of motive power, as for instance, an electric motor which is coupled to a reducing gear system contained within the housing 118, and the low speed shaft of which carries the driving sprocket wheel 119. The electric motor is not separately shown in the drawings as it may be included in the housing 118 or may be to one side of the housing 118. The reduction gearing may be any conventional reduction gearing merely to reduce the speed of the driving pinion 119 to the comparatively slow speed required for driving the ironer, and for obtaining the relatively high torque required.

The electric motor driving through any suitable reduction gearing is preferably connected directly to the main roll through the sprocket chain 120 and the sprocket wheel 121, as for instance on the right side or at the right end of the machine, as indicated at Figure 4. At the opposite end of the machine a gear 122 is secured to the main shaft 12 or to the main roll which is in mesh with a driven pinion 123 on the auxiliary roll 68 or on the shaft which carries the auxiliary roll, thereby imparting rotary motion to the auxiliary roll; the ratio between the driving gear 122 and the driven pinion 123 being such as to give the auxiliary roll approximately the same peripheral speed or linear speed as that of the main roll. A driving sprocket wheel 124 is also secured to the same end of the main roll for driving the two aprons 91 and 107, respectively. The sprocket wheel 124 is connected directly to an operating sprocket 125 on the driving roll 108 of the apron 107, through a suitable sprocket chain 126. At the forward left hand side of the machine, a counter-balanced take-up arm 186 is pivotally carried on the intermediate frame 13a, the arm 185 at one end is provided with a guide roller 187 to retain the sprocket chain in driving relation with the sprocket 125. A second driving sprocket wheel 127 (Figure 3) is provided on the shaft of the driving roll 108, from which a sprocket chain 128 transmits the

motion to a driven sprocket wheel 129 on the driving roll 92 or on the shaft of the driving roll 92, and thereby activating the feed-in apron 91.

As illustrated in Figure 3, both the feed-in apron 91, as well as the ironing and conveying 5 apron 107, may be either "solid" or sectional, as shown with the sections more or less closely spaced to each other.

A series of thin flat metallic strips are supported fixedly at their upper ends in the clamp- 10 ing bar 131, and extending between the roll 68 and the ironing surface of the chest 69 so as to strip the work from the roll 68 and to feed it onto the main roll 11. The strips 130 are generally resilient metallic strips having a com- 15 paratively small transverse dimension so that they will not interfere with the action between the auxiliary roll 68 and the steam chest 69.

At the discharge point on the roll 11, a series of pivotally mounted stripper fingers 132 are 20 provided, pivoted upon a common pivot 133 and held against the surface of the padding on the main roll 11 by counter-weighted arms 134, having adjustable counter-weights 135. The fingers 132 also carry guiding extensions 136 which guide 25 the work onto the receiving side of the apron 107.

A safety plate or guard 137 may be provided directly above the discharge zone of the feed-in apron 91, pivoted at 138 and 139, and having its lower edge extending to close proximity of the 30 apron 91 so that any accidental extension of the operator's hands or fingers into close proximity of the auxiliary roll 68 will cause the plate or guard to be deflected in the direction of the arrow 140. The pivot 139 is in turn connected through 35 the arm 141, the connecting link 142 and the arm 143 on shaft 143b, arm 143 being provided with a trigger finger 143a which is adapted to actuate a control lever 144 of the electrical controller 145, so that any slight deflection of the 40 plate will cause the button or plunger 146 of the controller to be pressed and stop the machine in its entirety, the controller is also provided with a reset or starter plunger 146a.

A pair of similar indicators 147 and 148 may 45 be provided upon pivots 149 and 150, and connected to the main roll bearings 22 and 23 through the connecting links 151 and 152 for indicating the pressure setting of the rolls. The indicators 147 and 148 may be made to traverse 50 over suitably graduated dials 153 and 154.

The heating of the steam chests is effected through suitable manifolds, such as the manifolds 106, 155, 156, 157, and 158, which are connected to the successive sections of the chests in 55 a manner similar to that indicated in the co-pending application Serial Number 756,517. The auxiliary steam chest 69 is provided with a similar manifold member 159 which extends across the successive sections and is bolted or otherwise 60 fastened thereto, and is provided with both the inlet passageways 160 and the discharge passageways 161.

A suitable steam supply line 162 may be provided for supplying steam to the various steam 65 manifolds, as for instance, through suitable steam branch lines 163, leading to the intake 160 of the manifold 159 on the auxiliary shaft and branch lines 164 and 165, leading to the intake manifolds 156 and 106, respectively, of the lower 70 chest, and a flexible connection (suitably steam-tight), 166 leading to the intake manifold 158 of the upper steam chest. The steam return or discharge lines are similarly arranged as indicated particularly in Figure 4, with a common 75

return line 167 and suitable auxiliary branch return lines 168 and 169, connecting the return manifolds 161, 155 and 151, respectively. A suitable vacuum pump 170 is provided on the machine directly connected, preferably, to the high speed shaft of the motor. The intake opening of the vacuum pump is connected by pipe 171 to the vacuum or suction manifold openings 172, 173 and 174 at the ends of the respective steam chests through suitable suction connections 175, 176 and 177. By this latter means, the suction is provided on all the suction openings 179 on the operative faces or operative surfaces of the steam chest, thereby to remove the vaporization 15 from the "work" and to effect a quicker drying of the "work."

The work is initially laid over the rail 180, as indicated in Figure 1, with the basket-like support 181 serving to retain the inner end of the 20 work. The work at the outer end or edge 182 of the work is then fitted onto the feeding apron 91.

By virtue of the vapor relief and also by virtue of the suctional vapor relief afforded the suction 25 ports in the ironing surfaces of the steam chests, the padding of the main roll, as well as the padding of the auxiliary roll, may be formed of a relatively firmer or harder material. Thus, by virtue of the relief afforded to the vaporization 30 from the laundry, the rotor padding may be made less absorbent to steam or vapor because the elimination of the vapor arising from the work does not depend entirely upon absorption in the padding. In this manner, a padding of relatively 35 firm felt, as for instance, woolen felt, may be used with a surface of suitably woven canvas, merely to give it a strengthening exterior surface resistant to wear. By virtue of this relatively 40 harder padding surface the laundry is given a smoother and glossier finish when rubbed up against the ironing surface of the steam chest. Thus, a smoother and glossier finish is obtainable on the "work."

The upper and lower steam chests or the juxtaposed steam chests which surround the main roll and also the auxiliary steam chest which cooperates with the auxiliary roll 68 are of the sectional aluminum or aluminum-alloy construction 45 or of the sectional non-ferrous construction disclosed in copending application Serial Number 50 756,517, now matured into Patent No. 2,057,988. By the use of aluminum or aluminum-alloy steam chests a more rapid transfer of heat is obtainable. Moreover, by the avoidance of the pitting 55 and scaling on the inside of the steam chests, common with the conventional ferrous construction, the heat transfer qualities of the chests are maintained uniform throughout the life of the 60 machine, and any irregularities in heat transfer are avoided.

Likewise, the aluminum or aluminum-alloy surface imparts to the working a somewhat different and more desirable finish than is imparted thereto by iron steam chests, and this is so by 65 virtue of the relatively softer ironing surface provided by aluminum, aluminum-alloy, or other

non-ferrous materials, such as copper-alloys and magnesium alloys.

The upper chest 17 has spaced from its outer surface a sheet metal casing 183 which is secured to the end plates 13b and 14b, the space between 5 the steam chest 17 and the casing 183 is filled with a heat insulating material 184 preferably asbestos to retain the heat within the steam chest.

The main drive shaft of the machine which is driven by the motor 118 and operates the vacuum 10 pump 170 is also connected to a magnetic brake 185 which is in electric connection with the electric controller 145 in order to positively stop the movements of all parts of the machine simultaneous with the breaking of the electrical circuit 15 by the controller 145.

Having thus described the invention, what is hereby claimed as new and desired to be secured by Letters Patent, is:

1. A laundry ironing machine comprising roll- 20 supporting means, a single revoluble main roll carried by said roll-supporting means, a plurality of generally oppositely disposed non-rotatable steam chests arranged around said main roll and adapted to bear against the operative surface 25 thereof, one of said chests being stationary and adapted to coat with an auxiliary ironing apron disposed at the rear thereof and means for adjustably moving the rest of said plurality of steam chests and the axis of the roll for varying the 30 pressure exerted by each of said chests on said roll without affecting the relative positions of said stationary chest and its coating auxiliary ironing apron.

2. A laundry ironing machine comprising a 35 revolvably mounted main roll, a plurality of generally oppositely disposed non-revolvable steam chests having heated ironing surfaces in operative contact with said main roll, one of said 40 chests being stationary and coating with an auxiliary ironing apron along the rear thereof, and manually operable means for simultaneously and uniformly varying the ironing pressures exerted by said main roll upon each of its associated steam chests without affecting the relative 45 ironing pressure between the rear of said stationary steam chest and its associated ironing apron.

3. A laundry ironing machine including a steam chest having an outer convex ironing surface adapted to cooperate with an ironing apron disposed at the rear thereof and having a concave inner ironing surface, said ironing apron and said chest being relatively fixed in a direction 50 normal to the path of the apron, a single vertically adjustable main roll having its periphery 55 cooperating with the inner concave ironing surface of said chest, and a second concave-surfaced steam chest contacting the periphery of said main roll generally opposite the first chest, said second 60 chest being radially adjustable relative to said main roll, and means for simultaneously varying the ironing pressure between said roll and both 65 said chests, without disturbing the ironing pressure between the outer surface of the relatively fixed chest and its coating ironing apron.

CLAUDE J. WEST.
